(57) **CLAIM**

The ornamental design for an LED strip light, as shown and described.

DESCRIPTION

FIG. 1 is a front, right side, top perspective view of an LED strip light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front, right side top perspective view of the LED strip light when it is in use.

The broken lines depict portions of the LED strip light that form no part of the claimed design.

The LED strip light is shown with a symbolic break in its length and the appearance of any portion of the LED strip light between the pairs of break lines forms no part of the claimed design.
